US00D360960S

United States Patent [19]

Wedell et al.

[11] Patent Number: Des. 360,960

[45] Date of Patent: ** Aug. 1, 1995

[54] **COMBINED QUARTZ HALOGEN FLOOD LIGHT ASSEMBLY AND SENSOR HOUSING**

[75] Inventors: **Mark T. Wedell**, Germantown, Tenn.; **J. D. McIngvale**, Hernando, Miss.

[73] Assignee: **Thomas & Betts Corporation**, Memphis, Tenn.

[**] Term: **14 Years**

[21] Appl. No.: **26,256**

[22] Filed: **Jul. 22, 1994**

[52] U.S. Cl. **D26/63**

[58] Field of Search **D26/61, 63, 65; 362/269, 275, 282, 285, 394, 418, 419, 421, 427**

[57] CLAIM

The ornamental design for an combined quartz halogen flood light assembly and sensor housing, as shown and described.

DESCRIPTION

FIG. 1 is a top perspective view of the assembly of the subject invention;

FIG. 2 is a front elevation view of the assembly of FIG. 1;

FIG. 3 is a left side elevation view of the assembly of FIG. 2;

FIG. 4 is a top plan view of the assembly of FIG. 2; and, FIG. 5 is a bottom plan view of the assembly of FIG. 2.

FIG. I

FIG. 2

FIG. 3

FIG. 4

FIG. 5
